CONTROL APPARATUS

Howard S. Beakes, Wilkinsburg, Pa., assignor to
The Union Switch & Signal Company, Swiss-
vale, Pa., a corporation of Pennsylvania

Application April 8, 1942, Serial No. 438,129

5 Claims. (Cl. 246—120)

My invention relates to control apparatus, and it has particular reference to the provision of novel and improved control apparatus and to the organization of such apparatus into novel and improved control systems of the class arranged for use in connection with a stretch of railroad to detect obstructions falling or sliding onto the right-of-way of the railroad.

It has been proposed heretofore to provide slide detector fences along the right-of-ways of railroads at locations where obstructions to the right-of-ways are likely to occur due to land or snow slides, falling rocks or trees, or the like. These fences are made up of one or more units, each comprising a pair of fence sections which extend in opposite directions from a mid point and which are anchored at their respective remote ends, and a circuit controller operatively connected with the adjacent free ends of the fence sections and arranged to govern signals controlling traffic on the railroad. In such systems, latch or trip type controllers usually are employed and the parts are adjusted so that the fence sections are normally stretched tight but that whenever either fence section is struck by a falling object of sufficient size to cause a dangerous condition to exist should the object lodge on the right-of-way, the section will deflect to trip off or operate the contacts of the associated controller. In order to adjust the apparatus, it is customary to provide suitable means, such as turnbuckles, for increasing or decreasing the tension to obtain the desired degree of tightness in the fence sections. This, of course, requires considerable attention from maintainers in order to compensate the fences for the various ranges of ambient temperature conditions, since with the length of fence sections employed, often reaching 400 feet or more, considerable expansion and contraction in the fence sections occur due to changes in ambient temperature. The compensation made available by the use of turnbuckles is of course limited in scope to be effective in a small range of temperatures and does not provide means for automatically compensating for relatively wide variations in temperature. For example, a section adjusted to obtain the proper tension when the ambient temperature is high, as during a hot autumn day, might be caused during a succeeding cold night to contract enough to trip off the circuit controller. On the other hand, a fence section adjusted to the proper tension when the ambient temperature is low might be caused due to a sudden rise in the ambient temperature to expand to an extent sufficient to make the fence slack

and thus permit the passage of obstructions without tripping off the controller.

In view of the above-mentioned and other important considerations, it is an object of my invention to provide novel and improved systems for detecting obstructions falling or sliding onto a right-of-way, arranged to be automatically compensated for changes in ambient temperature.

Another object is to provide novel and improved slide detector fence systems arranged to avoid false operations of the systems due to variations in ambient temperature.

A further object is to provide novel and improved forms of circuit controllers designed to compensate automatically for changes in ambient temperature when incorporated into slide detector fence systems.

An additional object is to incorporate pairs of fence sections and the associated circuit controllers into fence units arranged to compensate for expansion and contraction in the fence sections caused by changes in ambient temperature.

Another object is to provide novel and improved forms of circuit controllers particularly well adapted for use in slide detector fence systems.

Another object is to provide novel and improved forms of slide detector fence systems.

The above-mentioned and other important objects and characteristic features which will become readily apparent from the following description, are attained in accordance with my invention by employing a pair of fence sections each having its free end operatively connected with a circuit controller and arranged to effect an operation of the controller when and only when one of the sections is stressed by a force exerted thereon not balanced by a force of substantially equal magnitude exerted on the other section.

I shall describe several forms of apparatus embodying my invention, and shall then point out the novel features thereof in claims.

In the accompanying drawings, Fig. 1 is a diagrammatic view showing a slide detector fence system embodying my invention. Fig. 2 is an isometric view showing on an enlarged scale one form of an improved circuit controller embodying my invention and adapted for use in the system represented in Fig. 1. Fig. 2a is a side sectional view showing in more detail a portion of the controller represented in Fig. 2. Fig. 3 is an isometric view showing a modified form of the circuit controller represented in Fig. 2, and also embodying my invention. Fig. 4 is a front eleva-

tional view, partly in section, illustrating another modification of the circuit controller represented in Fig. 2, and which other modification also embodies my invention. Figs. 5 and 6 are views showing portions of the apparatus represented in Fig. 4. Fig. 7 is a view illustrating a modified form of the circuit controller illustrated in Fig. 2, and which modified form also embodies my invention. Figs. 8a, 8b, 8c and 8d are diagrammatic views illustrating various organizations of fence sections arranged for use in slide detector fence systems, and also embodying my invention. Figs. 9, 10, 11 and 12 are diagrammatic views illustrating another form of circuit controller embodying my invention. In each of the several views, similar reference characters have been employed to designate corresponding parts.

Referring to Fig. 1, a slide detector fence system of the class employed along the right-of-way of a railroad at locations such as at cuts, at the bases of rocky slopes, or any other locations where an obstruction to the right-of-way is likely to occur due to sliding or falling objects, is represented as comprising a pair of fence sections B and C and an associated circuit controller D. The fence sections are preferably of substantially equal lengths and each comprises a span of wire 1, which spans extend in opposite directions from the location of the controller. Each span is supported by end posts 2 and as many intermediate posts 3 and 4 as the length of the span makes desirable or necessary. The end posts 2 are securely anchored, as by imbedding their lower ends in concrete foundations, and if desired auxiliary posts 6 may be utilized as shown for bracing such end posts. The intermediate posts 3 and 4 may be maintained upright by being imbedded either in concrete, as in the case of posts 3, or in earth as is the case of posts 4.

Each span of wire 1 is rigidly fastened or anchored to the associated end post 2, and is slidably secured to each of the intermediate posts 3 and 4 in such manner as to be free to move longitudinally with respect to these posts. Each span extends a short distance past its associated post 3 and is secured to a tension bar 7. The two tension bars 7 are spaced apart as shown and are connected together through tensioning means, each preferably including a coupling member 8, a spring 9, and a turnbuckle 10 for increasing or decreasing the tension in the associated spring 9. The parts are proportioned and turnbuckles 10 are so adjusted as to cause the two spans of wire to be stretched tight, but whenever either section of fence is struck by a falling object having a size sufficient to create a dangerous condition should the object lodge upon the associated right-of-way, the fence section will deflect and cause its associated tension bar 7 to move toward its associated post 3.

Each tension bar 7 is operatively connected with circuit controller D mounted on an upright post 12 secured to a rigid foundation 13 at a location intermediate the two tension bars. Circuit controller D may take different forms, one of which is represented in Fig. 2 as comprising a suitable housing 15 provided at its forward side with a hinged cover 16 through which access to the operating parts of the controller may be obtained for adjustment or repair of the parts. Housing 15 is provided in its opposite sidewalls with guideways which slidably receive two operating members or plungers 18a and 18b operatively connected one with each tension bar 7, re-

spectively, in such manner that a longitudinal movement of either bar 7, caused by a lateral displacement of its associated fence section, will cause a corresponding longitudinal movement of the associated plunger 18a or 18b, as the case may be.

The plunger members 18a and 18b are arranged in parallel relation and hence are disposed out of axial alignment and are spaced apart for operation in a plane defined by the longitudinal axes of such members, as can be seen from an inspection of the drawings. The free ends of the plunger members are operatively connected with contact operating means for causing operation of an associated set of contacts whenever either plunger member is caused to move due to a lateral deflection of its associated fence section. Various different forms of contact operating means may be operatively connected with the plunger members 18a and 18b, and one such form is represented in Fig. 2 as comprising an operating block or cam basket 23 supported for longitudinal sliding movement in any suitable manner, as by providing projections 24 (see Fig. 2a) on the block cooperating with keyed channels 25 provided in the rear wall of housing 15. Block 23 preferably has its upper face (as viewed in the drawings) slotted for receiving a connecting link 26 rotatably mounted on a pin or shaft 27 journaled in the slotted upper portion of the block. The two plunger members 18a and 18b have their free ends slotted for receiving one end or the other of connecting link 26, and each plunger member is provided with a pin 28 which cooperates with an open-ended slot provided in the associated end of the connecting link.

Block 23 further comprises a supporting ledge 29 adapted to be engaged by a roller 30 provided on a contact operating member 31 disposed for vertical movement and slidably mounted in a supporting arm 32 secured to the rear wall of housing 15. In the normal condition of the apparatus, as represented in Fig. 2, roller 30 rides on and is supported by ledge 29, whereby member 31 is maintained in an upper position (as viewed in Fig. 2) against the bias of gravity and of a spring 33 encircling member 31 and disposed between supporting arm 32 and a collar 34 provided on member 31. In the upper position of the contact operating member, a contacting element 35 secured to but insulated from member 31, bridges a pair of contact fingers 36 suitably supported in housing 15. Other contact fingers 37 may be provided in housing 15 and be disposed to be bridged by element 35 when contact operating member 31 operates to its lower or operated position, as will be made clear presently.

Circuit controller D and the slide detector fence system as a whole operate in the following manner: Whenever either fence section is struck by a moving mass, such as by a slide or a large object like a tree or rock, the lateral pressure on the wire span forces the span to deflect laterally and move longitudinally through its loose fastenings by which it is supported by the intermediate posts 3 and 4. This longitudinal movement of a wire span is transmitted through the associated tension bar 7 to the plunger member 18a or 18b, as the case may be, associated therewith, and causes that member to move toward its associated post 3. For example, should a slide strike section C of Fig. 1, plunger member 18b is caused by the resulting deflection of the fence section to move toward its associated post 3, or from left to right as viewed in the drawings. To a limited extent,

the other plunger 18a may likewise be caused to move in the same direction due to the forces transmitted through the springs 9 from section C to the other section B. These forces are, however, largely absorbed in the springs 9, and the other fence section B, being anchored at its remote end and adjusted initially taut, is limited in expansion, hence the distance through which plunger 18a operates is quite small with respect to the distance through which the other plunger operates. Connecting link 26 will therefore rotate about an axis through the upper pin 28 that connects link 26 to plunger 18a, and block 23 will be moved to the right, thereby causing ledge 29 to be moved out of supporting relation to roller 30. Block 23 is preferably so constructed (see Fig. 2) as to have a sloping shoulder which will engage roller 30 after the ledge 29 is removed from supporting relation to the roller, and such sloping shoulder will exert a positive force on the roller to drive contact operating member 31 from its normal to an operated position, with the result that contacts 36 are no longer bridged and contacts 37 become bridged. These contacts 36 and 37 may be interposed, as is the usual custom, in the control circuits of wayside signals governing traffic on the associated stretch, and may be utilized to cause such signals to display either "caution" or "stop," whichever indication is desired, until the obstruction is removed and the circuit controller is restored to its normal condition in a manner to be made clear presently.

It is, of course, readily apparent that if fence section B is struck by a moving mass, the deflection of that section will cause plunger 18a to move from right to left, and will cause block 23 to move also to the left to remove ledge 29 from supporting relation to roller 30, and to bring a shoulder formed on block 23 into engagement with roller 30, whereupon contact operating member 31 will be caused to assume its operated position. The contacts of controller D are, therefore, caused to operate whenever either fence section is caused to deflect by a force not substantially balanced by a force of equal magnitude exerted on the other section.

The slide detector fence system, incorporating controller D, is arranged to be self-compensating for variations in ambient temperature. That is to say, whenever there is an expansion or contraction of the fence sections, the tension bars 7 are caused to move away from or toward their associated posts 3, respectively. Since the wire spans of each section are of substantially equal lengths, any variation of the ambient temperature that might cause an expansion or contraction in one fence section will cause a corresponding expansion or contraction in the other fence section. The variations in the lengths of the fence sections being substantially equal, each tension bar 7 will move toward or away from its associated post 3 an equal amount. These movements of the tension bars cause corresponding movements of the plunger members 18a and 18b operatively connected therewith, but do not effect an operation of the contact of controller D. This follows from the fact that when plunger members 18a and 18b are caused to move in opposite directions through substantially equal distances, connecting link 26 is caused to rotate about an axis through its pivot 27 but is not caused to have translatory motion. Block 23 accordingly is caused to remain substantially unmoved, and ledge 29 likewise is unactuated so that contact operating member 31 retains its contacting mem-

ber 35 in bridging relation with contacts 36. The contacts of controller D are, therefore, unactuated when plunger members 18a and 18b move through substantially equal distances in opposite directions due to balanced variations in the stresses in the two fence sections.

It should be noted that whenever operating block 23 is caused to move its supporting ledge 29 out of supporting relation to roller 30, contact operating member 31 is then caused to operate from its normal to an operated position due to a combination of forces exerted on the member. These forces comprise (1) gravity, (2) the force of spring 35 and (3) the force exerted by the shoulder of block 23 on roller 30. This last force may not always come into action but will do so should the movement of member 31 be restricted or delayed by friction or a binding of the parts, hence this positive "force-down" feature insures against a failure of member 31 to drop. The spring force of spring 35 will act to move roller 30 beyond mechanical contact with block 23, thereby isolating the contact structure from the operating portion and providing protection for the contact structures should a fence section be ruptured, or otherwise be caused to operate its plunger member abruptly back to its normal position.

A modification of the contact operating means just described is illustrated in Fig. 3, wherein the free ends of the plunger members 18a and 18b are provided with confronting and matching racks 20 which are engaged by a pinion gear 21 having its axle 22 journaled in suitable openings provided in the two side pieces of a freely movable yoke member Y1 which encloses the ends of the plunger members. Suitable contacting means, such as a plug receptacle 40 secured to a support, and a cooperating plug 41, are operatively connected with yoke Y1 as by means of a chain or rope 42 fastened to plug 41 and then looped over a pulley 43. The two ends of the chain are secured to yoke Y1 so that a longitudinal movement of the yoke in either direction will withdraw plug 41 from engagement with receptacle 40.

Whenever either plunger member 18a or 18b is caused to move longitudinally due to a lateral deflection of its associated fence section, gear 21 is caused to rotate and move in the same direction as that of the operated plunger member, whereupon yoke Y1 also moves in the same direction to disconnect plug 41 from receptacle 40. Should, however, the two plunger members move in opposite directions for substantially equal distances, gear 21 will then rotate but yoke Y1 will not move longitudinally with respect to receptacle 40, hence under such conditions, plug 41 will not be actuated. The arrangement shown in Fig. 3 is, therefore, self-compensating for variations in ambient temperature. In addition, the parts are arranged so as to avoid all possible injuries to the contacting members should a fence section be ruptured, or otherwise be caused to operate its plunger member abruptly back to its normal position after an operation thereof due to a deflection of a fence section.

Another form of contact operating means is represented in Fig. 4, wherein freely movable yoke member Y1 enclosing and operatively connected with the free ends of plunger members 18a and 18b by the engagement of gear 21 with the racks 20 formed on the plunger members, is provided with a cammed surface having two opposing sloping shoulders or sides either of which will operatively engage a contact operating plunger 46 slid-

ably mounted in an opening 47, disposed substantially at right angles to the line of movement of yoke Y1, provided in a supporting member 48 secured to housing 15. Plunger 46 is biased, as by a coil spring 49, into engagement with the cammed surface of member 45 of yoke Y1, and as can best be seen in Fig. 5, has a laterally extending slot 50 for cooperating with a beveled or tapered locking dog 51 (see Fig. 6) formed on or secured to a latch member 52. Latch member 52 is slidably mounted (see Fig. 4) in axially aligned openings 53 and 54 provided in member 48 at right angles to opening 47, and is provided with biasing means, such as a spring 57 bearing against a shoulder on member 52 and a surface of supporting member 48, for biasing dog 51 into engagement with plunger 46.

Plunger 46 normally occupies the position in which it is represented in Fig. 4, and yoke Y1 normally is positioned as shown so as to have its cammed surface engaged by plunger 46 at a point substantially midway between its sloping sides or shoulders. In this condition of the apparatus, dog 51 of latch 52 is forced by spring 57 into engagement with the side of the plunger. When yoke Y1 is moved longitudinally due to a deflection of either fence section, one or the other of the two sloping shoulders of cam member 45 engages plunger 46 to depress it to a position such that slot 50 and beveled dog 51 are in alignment. The dog 51 accordingly is forced into slot 50 and due to its taper forces the plunger down and causes it to be actuated out of engagement with the surface of cam 45.

The movement of plunger 46 is utilized to control contacts interposed in the control circuits of the associated wayside signal system. These contacts may be operatively connected with plunger 46 to be opened or closed, as desired, when the plunger is caused to operate, or as shown, the contacts may be operated by the movement of latch member 52 resulting when plunger 46 is depressed. The particular contact arrangement shown is thus merely illustrative and comprises two contact fingers 55 and 56 suitably supported in housing 15 and biased into engagement with each other to form a circuit controlling contact 55-56 when plunger 46 is in its normal position. When plunger 46 is depressed due to the longitudinal movement of cam 45, and is forced out of engagement with cam 45 by the action of tapered dog 51 on latch member 52, an insulated tip on member 52 engages contact finger 56 to operate it away from its cooperating finger 55, thereby opening contact 55-56.

In the operated position of the circuit controller, plunger 46 is latched out of engagement with yoke Y1 due to the keying action of dog 51 in slot 50. As a result, therefore, the yoke member Y1 is free to move after operation of the contact has been effected, without affecting in any manner either the contacts incorporated into the controller, or the plunger 46 latched in its operated position. It follows that with plunger 46 latched out of engagement with yoke Y1, and with the yoke free to move after having caused an operation of plunger 46, protection is afforded against possibility of damage to the apparatus should relatively large stresses be set up in a fence section when a slide or object strikes and passes a section. In any case where a fence section is deflected and then is caused to rebound back to its normal position upon passage of the object, the stresses released will be absorbed in the tensioning springs and other portions of the fence sys-

tem, and will not be transmitted to plunger 46, hence there is no possibility of jamming, breaking or injuring the plunger and its cooperating latch member 52 and contacts.

5 After an operation of the controller has been effected, the apparatus may be restored to its normal condition if the fence sections are in their respective normal positions, by manually operating latch member 52 against the force of its 10 spring 55 to the position where tapered dog 51 clears slot 50 of plunger 46. The plunger 46 accordingly is forced into engagement with yoke Y1, and latch member 52 is caused to hold its tapered dog 51 in engagement with the side of plunger 46. In this condition of the apparatus, the control contacts are in their normal positions, and the circuit controller is in its normal condition as illustrated in Fig. 4.

A circuit controller arranged to incorporate the apparatus represented in Fig. 4 is of course self-compensating for ambient temperature variations, since opposing movements of the two rack members 18a and 18b cause gear 21 to rotate but do not cause yoke Y1 to move longitudinally with respect to plunger 46, hence a contraction or an expansion of the two fence sections caused by a variation of the ambient temperature will not cause operation of plunger 46 and the contacts operatively associated therewith.

30 The contact operating means just described 20 may be employed in connection with an actuating member 60 secured to each of the two tensioning bars 7 of the fence section. In such an arrangement, shown in Fig. 7, the cammed surface 45 is 25 formed directly on or secured to operating member 60, which member preferably has one of its two ends yieldingly connected to one and non-yieldingly connected to the other of the two fence sections, while the other end of bar 60 is yieldingly connected to the other and non-yieldingly connected to the one fence section, respectively. The remainder of the apparatus (not shown) of 35 this form of controller may be of any of the forms shown respectively in Fig. 2, 3 or 4 as desired, and 40 for the purpose of example the upper portion of plunger member 46 is represented in the drawings to indicate that this plunger, together with its 45 associated latch member 52 and contacts operatively associated therewith and shown in detail 50 in Fig. 4, may be employed to cooperate in the manner described heretofore to cause operation of plunger 46 and the associated contacts whenever operating member 60 is caused to move longitudinally in response to a deflection of either of 55 the associated two fence sections.

The circuit controller represented in Fig. 7 does not itself provide compensation for expansion and contraction in the fence system due to ambient temperature changes, but if such compensation is desired, special arrangements of the two cooperating fence sections may be employed. Typical ones of these special fence sections are represented in Figs. 8a, 8b, 8c and 8d, and in each of these arrangements the fence sections are 65 operatively connected to the circuit controller operating member 60 in such manner as to effect a longitudinal movement of such member only in the event that either one of the sections is stressed by a force not substantially balanced by a force 70 of equal magnitude exerted on the other section. Whenever both sections are simultaneously stressed, as when the sections are caused to contract due to a change in the ambient temperature, the forces exerted on operating member 60 of 75 the controller are balanced and opposite in sense,

hence the resultant force is substantially zero in magnitude and no longitudinal movement of the member is caused to take place.

The fence sections shown in Figs. 8a-8d inclusive are, in general, operatively connected to operating member 60 of controller D through two equalizer members 61, one for each fence section. Each member 61 is connected to its associated fence section through a non-yielding connection, is connected to the other fence section through a yielding connection such as by a spring 62, and the two connecting members are pivotally secured to opposite ends of the operating member 60. In Fig. 8a, the yielding connection of member 61 to its associated section is established at the free end of the member, and the non-yielding connection to the other fence section is established at a point intermediate the two ends of the member. In Fig. 8b, the positions of the yielding and non-yielding connections are reversed. In Fig. 8c, both the yielding and non-yielding connections are effected at the free ends of the connecting members. In Fig. 8d, an equalizer member 63 pivotally secured at its mid point to one end of operating member 60 of the controller, has one of its ends yieldingly connected to one and non-yieldingly connected to the other fence section, and has its opposite end yieldingly connected to the other and non-yieldingly connected to the one fence section.

The arrangements of the fence sections shown in Figs. 8a-8d are all characterized by the fact that when substantially equal and opposite forces are exerted by the fence sections on the equalizing members, a resultant force of substantially zero magnitude is applied to the operating member 60 of the associated circuit controller. The arrangements permit a limited movement of the fence spans to take place, thereby allowing each span to elongate or shorten with changes in the ambient temperature. These changes in span length vary the tension in the springs 62 and the forces exerted on the associated connecting member, but being balanced and opposite in sense do not cause a longitudinal movement of the associated circuit controller operating member 60. When, however, unbalanced forces are exerted on the connecting members, as when one fence section is struck by a slide or moving object, then the resultant force causes longitudinal movement of the associated circuit controller operating member to cause in turn operation of the associated contacts. The fence section arrangements shown in Figs. 8a-8d may therefore be employed in connection with any one of the circuit controllers represented respectively in Figs. 2, 3, 4 and 7. The fence section arrangements have, however, particular utility in connection with a controller of the type represented in Fig. 7, and will cooperate therewith to provide such a combination with compensation for ambient temperature variations.

Another form of circuit controller embodying my invention represented in Figs. 9, 10, 11 and 12, comprises an equalizer bar 70 having its one end yieldingly connected to one section and non-yieldingly connected to the other section, and having its other end yieldingly connected to the other section and rigidly connected to the one section. Intermediate the ends of member 70 is secured a projecting actuating member 71 for cooperating with contact operating means comprising plunger 46 and associated latch member and contacts (not shown but similar, for example, in arrangement and construction to the plunger, latch rod

and cooperating contacts represented in Fig. 4). The actuating member 71 is operatively connected with plunger 46 through the medium of a bifurcated yoke member 72 secured to a jackshaft 73 supported in bearings 75 mounted in a casing or housing 74 enclosing equalizer bar 70 and attached to mid-post 12. The jackshaft 73 extends into another housing or casing 76 in which are contained plunger 46 and its associated latch rod and contacts, and also cam means for actuating the plunger. These cam means comprise two wing members 77 and a cooperating body member 78, all secured to jackshaft 73. Body member 78 is provided with slotted openings 79 for permitting the wing or ear members 77 to be adjustably secured by bolts 80 to the body member, thereby to provide means for adjusting the spread of the members. The tips of members 77 form actuating cam surfaces for depressing or actuating plunger 46, and the body member 78 may, as shown, form a portion of the cammed surface for limiting the upward travel of plunger 46 when the apparatus is in its normal condition.

The circuit controller represented in Figs. 9, 10, 11 and 12 is in its normal condition, as shown, whenever the stresses in the two fence sections are balanced. If, due to variations in the ambient temperature, the sections contract, equalizer bar 70 is caused to rotate about its mid point without effecting operation of yoke member 72. Should, however, a slide or object strike one of the sections and cause that section to deflect, then equalizer bar 70 is caused to pivot about its end that is inelastically connected to the other fence section, and the lateral movement of the equalizer bar will cause yoke member 72 to rotate jackshaft 73 and bring one or the other of the wing tips 77 into engagement with plunger 46, and thereby will cause the plunger to be depressed to a point such that it is latched up by its associated latch member hereinbefore mentioned.

Bifurcated yoke member 72 permits actuating member 71 to be readily disengaged therefrom should a relatively large deflection of the fence section occur. When this happens, the yoke member may be operated out of the path of actuating member 71 by means of a spring 82 (see Fig. 12) secured to housing 76 and bearing on a cam-shaped portion 81 formed on or secured to jackshaft 73. When shaft 73 is rotated to a point such that actuating member 71 disengages from yoke 72, spring 82 then bears against the side faces of element 81 and causes shaft 73 to continue to rotate so as to move both legs of the yoke out of the path of member 71. It follows that should an extremely large object or slide strike the fence section and cause a relatively large deflection to take place, actuating member 71 will be disengaged from yoke 72 and the yoke will be moved out of the path of member 71 so that if a rupture occurs in the fence section, or the object passes through the section and permits the section to rebound abruptly back to its normal position, the actuating member will be restored abruptly to its normal position but will not strike, jam, or injure the yoke member and its associated contact operating apparatus.

From the foregoing description of the various forms of circuit controller and fence section arrangements, embodying my invention, it is readily apparent that such apparatus when organized into slide detector fence systems provides compensation for ambient temperature variations and hence functions to improve the operation of the systems by reducing the necessity of frequent

adjustments of the fence sections' stresses, and also by reducing the possibility of improper operation of the systems due to variations in the ambient temperature. It is, of course, apparent that each of the different forms of circuit controllers shown in the drawings might be modified to incorporate features and structural arrangements shown in other forms of the represented controllers. For example, the yokes Y_1 of Figs. 3 and 4 may have associated therewith contact operating means of the type shown in Fig. 2 and involving ledge 29 , roller 30 and contact operating member 31 ; while operating block 23 of Fig. 2 may likewise have associated therewith contact operating means of the type shown in Fig. 3 or Fig. 4.

Although I have herein shown and described only a few forms of control apparatus embodying my invention, it is understood that various changes and modifications may be made therein within the scope of the appended claims without departing from the spirit and scope of my invention.

Having thus described my invention, what I claim is:

1. In a protective system for detecting obstructions falling or sliding onto the roadway of a railroad, of the class comprising a pair of fence sections extending along said roadway, each said section being anchored at one of its ends, and a circuit controller operatively connected to the free ends of said fence sections and arranged to govern signals controlling traffic on the railroad, the improvement consisting of the provision in such a system of a circuit controller comprising a housing, two plunger members one secured to the free end of each of said fence sections and slidably mounted respectively in opposite walls of said housing, an operating member slidably mounted for longitudinal movement, a connecting link rotatably mounted on a shaft journaled in said operating member and operatively connected with each of said plunger members for rotation about either of said members or said shaft according as only one or both of said plunger members moves longitudinally, and contact operating means operatively connected with said operating member for operation in response to a longitudinal movement of said operating member effected by a rotation of said connecting link about either plunger member but not by a rotation of said connecting link about said shaft.

2. In a protective system for detecting obstructions falling or sliding onto the roadway of a railroad, of the class comprising a pair of fence sections extending along said roadway, each said section being anchored at one of its ends, and a circuit controller operatively connected to the free ends of said fence sections and arranged to govern signals controlling traffic on the railroad, the improvement consisting of the provision in such a system of a circuit controller comprising a housing, two plunger members slidably mounted in opposite walls of said housing and secured to the free end of each of said fence sections, respectively, an operating member mounted for sliding movement, a connecting link

rotatably mounted on a shaft journaled in said operating member and operatively connected with each of said plunger members for effecting a movement of said operating member when either

5 plunger member moves in either direction but not when both plunger members move in opposite directions, a gravity biased member supported by said operating member, means for forcing down said gravity biased member when said operating member is caused to move, and contacts operatively connected with said gravity biased member and operated when such member is forced down.

3. In combination, a pair of fence sections, a circuit controller having a member for operating contacts in response to a longitudinal movement of said member, two bars connected to the opposite ends of said member respectively, an extensible connection from one of said two fence sections to one of said two bars and a non-extensible connection from said one fence section to the other of said two bars, and an extensible connection from the other of said two fence sections to said other bar and a non-extensible connection from said other fence section to said one bar, said extensible and non-extensible connections to each bar being arranged so as to effect a longitudinal movement of said member only in response to a lateral movement of either one of said fence sections.

4. In combination, a pair of fence sections, a circuit controller having a member for operating contacts in response to a longitudinal movement of said member, a bar connected intermediate its ends to one end of said member, an extensible connection between one of said fence sections and one end of said bar and a non-extensible connection between said one fence section and the other end of said bar, an extensible connection 40 between the other of said fence sections and said other end of said bar and a non-extensible connection between said other fence section and said one end of said bar, said extensible and non-extensible connections being effective to produce 45 a longitudinal movement of said member only in response to a lateral deflection of one but not both of said fence sections.

5. In a protective fence for a way comprising a pair of fence sections extending along said way, each said fence section being anchored at one end and movable at the other end, said movable ends being connected together by yieldable means which maintains the sections stretched tight while allowing for expansion and contraction, the combination with said fence sections of a circuit controller including a longitudinally movable operating member and a contact operated in response to longitudinal movement of said operating member, and means connecting said operating member with the movable ends of said two fence sections and effective to produce longitudinal movement of said operating member to operate said circuit controller in response to longitudinal movement of either fence section not balanced by a substantially equal and opposite movement of the other fence section.

HOWARD S. BEAKES.
